UNITED STATES PATENT OFFICE.

WILHELM DICKEL, OF BERLIN, GERMANY.

TWO-LATCH LOCK WITH SAFETY-CATCH.

No. 802,499.

Specification of Letters Patent.

Patented Oct. 24, 1905.

Application filed April 3, 1905. Serial No. 253,660.

To all whom it may concern:

Be it known that I, WILHELM DICKEL, a subject of the German Emperor, and a resident of Berlin, Germany, have invented certain new and useful Improvements in Two-Latch Locks with Safety-Catch by Means of the Latch, of which the following is a specification.

The lock most in use for the doors of rooms and halls is the two-latch lock with a spring-bolt. In order to prevent that such a door could be opened from the other side, special devices were hitherto required, such as a night-bolt, a second lock, and the like. According to the present invention the lock is secured against being opened by turning the latch in the direction the opposite of that in which it is opened, so that the opening of hall-doors by means of false keys can be easily prevented and without any special devices. To this end the roll-back of the lock is divided perpendicularly to the axis of rotation, so that each latch has a roll-back for itself, and the roll-back on the latch being turned in the opposite direction fixes or secures the bolt of the lock.

The accompanying drawings show a form of construction of the lock with a latch on both sides.

Figure 1 shows the case of the lock 17 open. Fig. 2 shows the same in a section on the line *m n* of Fig. 1 with the lower part omitted.

Similar numerals refer to similar parts throughout both views.

In the two-latch locks with a spring-bolt hitherto in use the latch could be turned only in one direction—for instance the latch 6 of Fig. 1 downward, whereby its thumb 2 gets into the position indicated by a dotted line and thereby pushes back the bolt 7 of the lock, and thus opens the door. If now, as done in this invention, the latch 6 is turned upward into the position 5, its thumb 2 gets into the position 1 and sets against a projection 13 of the bolt 7, so that the latter cannot be moved from the other side of the door. The superposed parts 3 and 4 of the roll-back have, as shown in Fig. 2, a mutual inner guide. They are held together at their contact-surface by a ring 12, which might, however, also be fastened to one of the roll-backs.

In order to fasten the pin 8 or 9 of the latch 6 or 5 in its roll-back 3 or 4, it is split longitudinally, and the end of it is excavated, as shown in Fig. 2. This cavity tapers toward the interior, while the hole of the roll-back tapers toward the outside. In the cavity is a

split piece 10 or 11 on a pin 18 or 19, which pin passes through the latch 6 or 5 and is threaded at the end. If the roll-back 20 is drawn tight, the parts of the pin 8 or 9 cleave or fork 60 asunder and the latch 6 or 5 is firmly secured in its roll-back 3 or 4.

It is immaterial whether both door-latches are fixed or are in the form of keys or whether a fixed latch and a key are used. 65

For hall-doors only a fixed latch is used, as a rule, while the door is opened from the outside by means of a key. Such a door is safely locked from the inside in the above-described manner. If the door is also to be secured from the outside, a second lock 22, with key 23, is used, the bolt 21 of which secures the bolt 7. In order to be able after releasing the safety device to open the door with the same key 23—that is to say, to push back 75 the bolt 7—there is either provided on the bolt 7 a projection matching the key 23, or, as shown in Fig. 1, a lever 24 is used. If now the key 23 is turned in the opposite direction, it turns the lever 24, and the latter pushes 80 back the bolt 7 by means of the projection 14.

In order to support the latch 6 or 5 in its horizontal position, a springy projection 15 has been provided, against which sets the thumb 16 of the roll-back 3. 85

If the door is to be secured on one side only, a projection 25 is provided, which prevents the roll-back from being turned in the opposite direction and into the position 1.

What I claim as my invention, and desire to 90 secure by United States Letters Patent, is—

1. In a two-latch lock with a spring-bolt and a roll-back the division of this roll-back vertical to its axis, and the device by which, in consequence of turning the latch in the opposite direction (direction of the arrow,) the bolt of the lock is secured in its closing position, so that the door is at once protected against being opened from the outside, substantially as set forth. 95

2. In a two-latch lock with a spring-bolt and a roll-back the arrangement that the pin of the latch (8 or 9) is split and that there is pressed into its wedge-like excavated end a splitting-piece (10 or 11,) which is placed on a pin 18 or 19 extending through the latch and which is drawn tight from the outside, substantially as set forth. 100

3. In a two-latch lock with a spring-bolt and a roll-back the arrangement of a second lock 22 serving to bolt the lock of the door, and the key 23 of which, if turned in the opposite 110

direction, also opens it, substantially as set forth.

4. In a two-latch lock with a spring-bolt and a roll-back a projection 25 which prevents one part of the roll-back from being turned into the locking position 1, substantially as and for the purpose set forth.

In witness whereof I have hereunto signed my name, this 15th day of March, 1905, in the presence of two subscribing witnesses.

WILHELM DICKEL.
